[57] CLAIM

The ornamental design for an aircraft deicer vehicle, as shown and described.

DESCRIPTION

FIG. 1 is a left, front perspective view of an aircraft deicer vehicle showing our new design;

FIG. 2 is a left side elevational view thereof;

FIG. 3 is a right side elevational view thereof;

FIG. 4 is a top plan view thereof;

FIG. 5 is a front elevational view thereof; and,

FIG. 6 is a rear elevational view thereof.

The broken lines shown in FIGS. 1 through 6 of the drawing are for illustrative purposes only and form no part of the claimed design.

FIG. 1

FIG. 2

FIG. 3
